(57) **CLAIM**

The Ornamental design for a handle for curb stop valve, as shown and described.

DESCRIPTION

FIG. 1 is a perspective view of a handle for curb stop valve showing my new design;

FIG. 2 is a right said elevational view thereof;

FIG. 3 is a left side elevational view thereof;

FIG. 4 is a front elevational view thereof;

FIG. 5 is a rear elevation view thereof;

FIG. 6 is a top plan view thereof; and,

FIG. 7 is a bottom plan view thereof.

The broken lines in FIGS. 1 and 7 illustrate environmental subject matter only and form no part of the claimed design.
